Primary Examiner — Kelley Donnelly*(74) Attorney, Agent, or Firm* — Koppel, Patrick, Heybl & Philpott**(57) CLAIM**

The ornamental design for a serving tray, as shown and described herein.

DESCRIPTION

FIG. 1 is a top, front, right side perspective view of a serving tray incorporating features of the present invention;

FIG. 2 is a top plan view of the serving tray shown in FIG. 1;

FIG. 3 is a bottom plan view of the serving tray shown in FIG. 1;

FIG. 4 is a front elevation view of the serving tray shown in FIG. 1;

FIG. 5 is a rear elevation view of the serving tray shown in FIG. 1;

FIG. 6 is a left side elevation view of the serving tray shown in FIG. 1, the right side elevation view, not shown, is a mirror image; and,

FIG. 7 is a top, front, right side perspective view of an alternative embodiment of a serving tray incorporating features of the present invention not comprising the top raised center portion.

Additional views of the embodiment shown in FIG. 7 are not depicted herein as they are the same as the views depicted in FIGS. 3-6 above;

The broken lines in FIG. 1 and FIG. 7 depict environmental subject matter only and form no part of the claimed design.
